UNITED STATES PATENT OFFICE.

JIM P. BUTTS, OF CARBON, TEXAS.

DRAFT-EQUALIZER.

1,250,964.

Specification of Letters Patent. Patented Dec. 25, 1917.

Application filed December 16, 1916. Serial No. 137,379.

To all whom it may concern:

Be it known that I, JIM P. BUTTS, a citizen of the United States, residing at Carbon, in the county of Eastland and State 5 of Texas, have invented certain new and useful Improvements in Draft-Equalizers, of which the following is a specification.

This invention has relation to draft equalizers, and has for an object to provide 10 a device of this character adapted to be secured to the draft tongue of an agricultural machine such as a binder whereby the machine may be drawn evenly and in a straight line, irrespective of the resistance which may 15 be applied unevenly to the sides of machine due to its operation, and whereby the draft animals may be suitably disposed at each side of the draft tongue and hitched to the equalizer to insure uniform travel of the 20 machine.

In addition to the foregoing my invention comprehends improvements in the details of construction and arrangement of parts to be hereinafter more fully described and particularly set forth in appended claim.

In the accompanying drawings in which similar and corresponding parts are designated by the same characters of reference throughout the several views in which they 30 appear:

Figure 1, is a view in plan of a draft equalizer, constructed after the manner of my invention, and illustrating its application to a draft tongue and

Fig. 2, is a transverse section taken on the line 2—2 of the preceding figure.

With reference to the drawings 1 indicates a draft tongue of conventional type and 2 indicates generally the draft equalizer applied thereto.

This draft equalizer includes a pair of superposed frame bars 3 disposed transversely of the tongue and secured to the upper side thereof through the medium of a 45 U-shaped bolt 4 which extends beneath the tongue with its terminals 5 projecting upwardly at each side of the tongue and through openings provided in the frame bars 3 for the reception of the said terminals. 50 Nuts 6 are applied to the threaded terminals 5 of the U-bolt whereby the frame bars may be secured to the tongue and suitable spacing blocks 7 are disposed between the bars 3 to dispose them in spaced relation for 55 a purpose which will be presently obvious.

The frame bars 3 are bent downwardly at

an angle from a point adjacent the longitudinal edges of the draft tongue as set forth in Fig. 2 and pivoted between the outer extremities of said bars at either end thereof 60 is a lever indicated at 8. Each lever is pivoted at substantially a point intermediate its ends to the ends of the bar 3 through the medium of a rivet, bolt or the like, indicated at 9.

Mounted on the draft tongue forwardly of the equalizer is a bracket 10 constructed of strap iron having an attaching portion whereby it may be secured to the tongue and a rear portion 11 spaced vertically from the 70 surface of the tongue to receive between the under side of the said surface and the tongue a pulley 12 mounted for rotation upon a bolt 13 which passes through said portion 11 of the bracket and the tongue. A flexible element 14 which may be in the nature of a cable, section of chain or the like is passed partly around the forward portion of the pulley 12 and is connected at its terminals to the inner adjacent ends of the links 8 80 through the medium of a series of perforations 15 provided in said ends of the levers. Thus, the ends of the flexible element may be secured in any of the perforations with a view to varying the leverage of the levers 85 8 for the purpose of evening the draft. To the outer ends of the levers 8 are secured swingletrees 16 forming a means for hitching the horses or other draft animals thereto.

Thus, it will be seen that with the flexible 90 element connected to the levers 8 in the manner set forth in Fig. 1 of the drawings the draft upon the machine will be more or less even. However, should it be desired to provide a greater draft upon one side of the 95 tongue than the other, owing to the uneven resistance to movement of the machine due to its operation, the terminals of the flexible element may be inserted in either of the perforations 15 until the draft is evenly distributed.

While I have thus illustrated and described my invention with some degree of particularity I realize that in practice various alterations thereover may be made, and 105 I therefore reserve the right and privilege of changing the form of the details of construction or otherwise altering the arrangement of the correlated parts without departing from the spirit of the invention or the 110 scope of the appended claim.

Having thus described my invention, what

I claim as new and desire to secure by Letters Patent is:

In a draft equalizer, the combination of a draft tongue, a frame including a pair of superposed plates extended transversely of the tongue and secured thereto in spaced relation, the ends of the plates being bent downward at an angle to the vertical, a pair of levers, one on each side of the tongue pivotally mounted between the outer ends of the plates at points intermediate the ends of the

levers, a pulley mounted on the tongue, a flexible element passed around the pulley and having its ends connected to the inner ends of the levers, and whiffletrees connected to the outer ends of the levers.

In testimony whereof I affix my signature in presence of two witnesses.

JIM P. BUTTS.
